UNITED STATES PATENT OFFICE.

JAMES H. KENNEDY, OF NEW ORLEANS, LOUISIANA.

SANITARY TOILET-SEAT COVER.

Application filed May 17, 1928. Serial No. 278,487.

This invention relates to an article of sanitation and pertains particularly to a sanitary toilet seat cover.

The primary object of the invention is to provide a seat cover designed primarily for use upon those types of seat which are split at the front portion and upon seats which are formed in sections, one of the novel features of the cover residing in the provision of means whereby the cover can be secured in position.

Another object of the invention is to provide, in a manner as hereinafter set forth, a toilet seat cover of the above described character having means to permit of its enlargement in the direction of its length and of its width.

A still further object of the invention is to provide a seat cover which may be divided in two portions for use upon two part seats, each of said portions having means associated therewith for attaching it to the adjacent or underlying seat or section.

The invention will be best understood from a consideration of the following detailed description taken in connection with the accompanying drawings forming part of this specification, with the understanding, however, that the invention is not confined to any strict conformity with the showing of the drawings but may be changed or modified so long as such changes or modifications mark no material departure from the salient features of the invention as expressed in the appended claims.

In the drawings:—

Figure 1 is a top plan view of the seat cover embodying the present invention;

Fig. 2 is a bottom plan view of the cover;

Fig. 3 shows diagrammatic views representing a cross section of the cover in original and extended condition;

Fig. 4 shows diagrammatic views of the cover in section through the middle thereof, showing the same open and closed;

Fig. 5 shows in detail a seat member receiving pocket and, diagrammatically, the manner in which the pocket receives a portion of the seat;

Fig. 6 shows a transverse fold in perspective and a diagrammatic view of the same opened out;

Figure 7 shows a longitudinal fold in perspective and a diagrammatic view of the same in open condition;

Figure 8 is a diagrammatic view taken transversely of the seat cover showing the same in position.

Referring now to the drawings in detail wherein like numerals of reference indicate corresponding parts throughout the several views the numeral 1 indicates as a whole, the seat cover embodying the present invention.

This cover is designed to be made of relatively heavy paper or a similar suitable material and is of generally circular design as shown and is provided with a central substantially circular opening 2.

The cover is provided adjacent the inner and outer edges with the circular lines of perforations 3 and 4, thus setting up a relatively broad central portion 5 and inner and outer flanges 6 and 7 respectively which, when the central portion 5 is in position upon the surface of the seat, are designed to be folded down to cover the inner and outer edges of the same.

The seat body is provided at one point on its outer edge with the extended portion 8, which portion is provided to overlie the rear of the seat upon which the cover is placed. The line of perforations 3 which is formed about the outer edge of the seat body is extended along the edge of this portion 8 to provide flanges along the sides of the same.

The edge of the opening 2 is provided at diametrically opposite points with the tabs 9 and 10 which, when the cover is in position, position at the front and back respectively of the seat. These tabs afford additional protection and increase the sanitary features of the device.

In order to adapt the seat cover to seats larger than those to which it could be applied as thus far described, means is provided whereby the overall measurements of the same may be increased. To this end the body of the cover is provided at diametrically opposite points with transverse rows of perforations 11 to permit the ready transverse division of the cover.

Overlying each of the lines of perforations 11 is a folded portion of the material of which the seat is formed, these folds, each of which is indicated generally by the numeral 12, comprising a relatively broad central portion 13 having a strip 14 along each edge folded under and secured at its free edge upon one side of the perforation line. It will be thus seen that upon tearing the cover transversely

along the lines 11, the size of the same can be increased lengthwise to the extent to which the folded bodies 12 can be opened out.

In order to permit the widening of the cover, folded bodies 15 and 15^a, similar to bodies 12, are secured at diametrically opposite points upon and extending lengthwise of the cover at the front and rear respectively of the same, each of these bodies comprising a broad central portion 16 and longitudinally extending integral side strips 17, the edges of which are secured to the body of the cover. In the folded bodies 12 the edges of the strips 14 are relatively close together while in the bodies 15, the edges of the strips 17 are separated a substantial distance and the body of the cover beneath each of these folded bodies is provided with two lines of perforations 18 and 18^a, each line being adjacent the edge 20 of a strip 17 as shown in Figure 2. As also shown in this figure and Figure 1, these lines of perforations extend from the outer edge of the cover inwardly as far as the circular line of perforations 4, thus when the cover 25 is torn lengthwise to permit widening, tabs 9 and 10 will not become detached, the line of tear only opening in the form of a V.

In order to permit the application of the cover to seats which are formed in two independent portions, the cover is provided at the front and rear and upon each side of the point of joinder between the strips 17 of the bodies 15 and 15^a, with the perforation lines 19. By this means the seat cover can be 35 divided by removing that portion at the front and rear, which lies between the attached edges of the bodies 15 and 15^a.

The cover is designed to be held in position by the pockets 20 and 21 which are secured to the under surface thereof at the front and rear of the same, there being two pockets at the rear and two at the front arranged adjacent and upon opposite sides of the bodies 15 and 15^a. These pockets 20 and 45 21 consist of sections of material of which the seat is formed and each has a lengthwise extending fold 22, the edges of the pocket which extend parallel to the fold being secured to the body of the central portion 5 of the cover.

When the cover is divided for use upon the two part seats above mentioned, each section of the cover has one of the portions of the seat extended through the pockets 20 and 21 55 thereon and is thus securely held in position thereby. It is, of course, obvious that one of the front and one of the rear pockets can be employed to maintain the cover in position upon a seat of the split type by simply 60 extending one of the horns thereof through these pockets.

When the seat cover is to be used upon those seats which are made up of four independent sections, that is seats having front 65 and rear openings and transverse side open-

ings, each of the pockets 20 and the pockets 21 may be engaged over an end of a section to hold the cover in position.

If the seat is of such size that the cover will not conveniently fit thereon, the cover may be 70 enlarged by forming a transverse division along the lines 11 and longitudinal divisions along the lines 19 at the front and at the rear, thus permitting the four sections of the cover thus formed to be spread apart until the cover 75 has been sufficiently increased in size to fit the seat. If the sections or folds 12, 15 and 15^a are not completely opened out, they will be positioned out of the way in the recesses between the ends of the seat sections. 80

The manner in which the pockets 20 and 21 may be opened up, or do open up to receive the seat sections is clearly shown in Figures 5 and 8, the seat being indicated in these figures 85 by the numerals 23.

From the foregoing description it will readily understood that a seat cover of the character described can be made to fit any size or type of seat and with the flange portions 6 and 7 turned downwardly and the flaps or 90 tabs 9 and 10 in position complete protection will be had.

Having thus described my invention, what I claim is:—

1. A sanitary toilet seat cover for seats of the split type, comprising a body of deformable material designed to overlie and conform to the outline of a seat, and pleated pockets carried by the body designed to be opened out to receive the ends of the seat to maintain the 100 body in position thereon.

2. A sanitary toilet seat cover, comprising a generally circular centrally opened body normally integral throughout and designed to overlie and conform to the outline of a 105 seat, and means whereby the body may be broken and the integrity thereof destroyed to form individual but connected portions to permit the body to be increased in size in the direction of one axis of the seat. 110

3. A sanitary toilet seat cover for seats of the split type, comprising a body of deformable material designed to overlie and conform to the outline of a seat, pockets carried by the body upon opposite sides of the longitudinal center for receiving the ends of the seat to maintain the body in position thereon, and means for increasing the size of the cover. 115

4. A sanitary seat cover comprising a centrally opened body of deformable material formed to conform to the curvature of a seat and having perforated tear lines formed transversely thereof, and folded extensible bodies secured to the cover body and overlying said tear lines to provide a connection between the portions of the body formed after the same has been separated along said lines. 120

5. A sanitary toilet seat cover comprising a flat body having a central opening formed therethrough and designed to overlie and 125

conform to a seat body, said flat body having a pair of lines of perforations formed at diametrically opposite points and extending from the inner to the outer edges thereof to 5 permit of the separation of the body into two portions, and extensible pocket elements carried by each of the two portions and designed to receive a portion of a two part seat.

6. A sanitary toilet seat cover of the character described, comprising a generally circular centrally apertured body having a line of perforations formed therethrough transversely of the medial portion, and pleats overlying and secured to the body at opposite 10 sides of the line of perforations designed to maintain the body as a unitary structure of increased size after dividing the body along said lines.

7. A sanitary toilet set cover of the character described, comprising a generally circular body having a central opening formed therethrough, said body having medial transverse and longitudinal lines of perforations designed to permit of its being divided into four 15 sections, and longitudinally and transverse- 20

25

ly extending pleats secured to the body, each of said pleats overlying and being secured at opposite sides of a line of perforations and acting after division of the body to maintain the parts in connected relation. 30

8. A sanitary toilet seat cover of the character described, comprising a generally circular body having a central opening formed therethrough, said body having medial transverse and longitudinal lines of perforations 35 designed to permit of its being divided into four sections, longitudinally and transversely extending pleats secured to the body, each of said pleats overlying and being secured at opposite sides of a line of perforations and 40 acting after division of the body to maintain the parts in connected relation, and a pleated expansible pocket carried by the under face of each of the four potential portions of the body to facilitate securing the same to a 45 divided seat.

In testimony whereof I hereunto affix my signature.

JAMES H. KENNEDY.
